UNITED STATES PATENT OFFICE.

A BERTSELL IRELAND, FRANK L. IRELAND, AND HERBERT A. IRELAND, OF NORWICH,
NEW YORK.

WINDING-MACHINE.

1,318,672.

Specification of Letters Patent.

Patented Oct. 14, 1919.

Original application filed October 6, 1910; Serial No. 585,622. Divided and this application filed November 29, 1915. Serial No. 64,158.

To all whom it may concern:

Be it known that we, A BERTSELL IRELAND, FRANK L. IRELAND, and HERBERT A. IRELAND, citizens of the United States, residing at 5 Norwich, New York, have invented certain new and useful Improvements in Winding-Machines, of which the following is a clear, full, and exact description.

This invention relates to winding mechanisms and is herein shown as embodied in a machine for slitting cloth or other fabrics into strips, folding the edges of the strips, and winding them into rolls. It will be understood, however, that the invention is 10 not limited to its illustrated embodiment or use, and that it is of general applicability in 15 the art to which it relates.

An object of the invention is to provide improved means for winding strips into rolls, 20 which is especially adapted for the convenient removal of the completed rolls. In the illustrated embodiment of the invention, a two-part winding shaft is so constructed and arranged that the parts may be separated and one may be removed from the machine with the completed rolls thereon, and 25 an important feature of the invention is the arrangement whereby the ends of the strips are clamped between the shaft parts to start 30 the winding.

Other objects and important features of the invention will appear from the following description and claims when considered in connection with the accompanying drawings, 35 in which—

Figure 1 is a perspective view of a preferred embodiment of the invention, this view showing the front, the top and the left-hand side of the machine;

Fig. 2 is a longitudinal section through the machine, this view showing the course 40 of the fabric through the machine;

Fig. 3 is a broken longitudinal section through the winding means, this view illustrating particularly the construction of the so-called split shaft;

Fig. 4 is a view showing the arrangement 45 of the gears for transmitting movement from the driving pulley to the different mechanisms; and

Fig. 5 is a detail perspective of the means for locking the split shaft in its bearings.

As hereinabove pointed out, the invention is shown as embodied in a machine for slit-

ting a web or sheet of cloth into strips, folding the edges of the strips, and winding the strips into rolls, but only so much of the illustrated machine will be described herein as is necessary for an understanding of the invention, the machine as a whole being fully described in our copending application Serial No. 585,622, filed October 6, 1910 for Letters Patent for improvements in winding machines, Patent No. 1,164,650, of which application the present application is a division.

The machine herein illustrated comprises a main frame 2 of such proportions as to support the operative parts of the machine within convenient reach of the operator. 70 Fixed in the frame 2 is a shaft 4, upon which is mounted to turn freely thereon a pulley 6 connected to any suitable source of power. Of the various mechanisms which make up the machine, some have their bearings in the main frame 2 and others have their bearings in a raised part of the frame which, for convenience, may be designated as the head 8. The head 8 is pivoted upon the fixed shaft 4, as shown in Fig. 2, and is normally held 80 rigid with the main frame by set screws 10 screwed into the main frame, and received in slots 12 in said head.

The machine comprises cloth holding means, means for tensioning the cloth longitudinally, means for tensioning the cloth laterally, slitting means, folding means, means for ironing out the folds, and the winding means which constitutes the subject-matter 85 of the present invention. Only a brief reference will be made to the means not herein claimed.

If the cloth or other fabric to be operated upon comes in a roll, it is preferably mounted upon the rod 14 to turn thereon in unwinding. If it comes in the form of a bolt or is merely folded, it may be supported outside of the machine and guided over the rod 14, suitable spacing members being clamped upon said rod to guide the particular width 100 of cloth being operated upon.

The means for putting the cloth under longitudinal tension comprises a roll 32 having a friction surface of some suitable material, such as sand-paper, the cloth passing over this roll and being made to turn the roll against frictional retarding means, comprising a friction wheel 36 fast upon

the shaft 38 which carries the roll 32, and a strap 34 which passes over said wheel and is pivotally connected at one end to the frame 2 and at its other end supports a weight-carrier 40, upon which different numbers and sizes of weights may be hung to vary the tension put upon the cloth by the roll 32.

From the means for putting the cloth under longitudinal tension, it passes to means which equalizes its lateral tension, and also serves to remove wrinkles or folds such as are commonly found in rolls of cloth, this means comprising a spreading roll having a series of slats 48 movable lengthwise of the shaft 52 upon which the roll is mounted. This means for tensioning the cloth laterally is more fully shown and described in the copending application hereinabove referred to.

From the tensioning means the cloth or other fabric passes over and turns a measuring roll 72, and it is then operated upon by the cutting means which comprises disk-cutters 132 and 134 mounted, respectively, upon shafts 130 and 136. These cutters are so spaced as to cut the web or sheet into strips of the desired width, and the strips then pass through folding means, comprising separate folding elements 144 mounted upon a rod 148 fixed in the head 8. The folders 144 fold over the edges of the strips, and these folded edges are then acted upon by ironing means, the strips passing over a heated roll 162 with which coöperates a pressure roll 164. From the pressing or ironing means the strips pass to the winding mechanism, which is the particular subject-matter of the present invention.

The novel winding mechanism comprises a split shaft, shown in detail in Fig. 3, said shaft being provided at one end with a gear 170 which receives its motion from the gear 138 through idlers 172 and 174. At its other end the split shaft is provided with a hand wheel 176. Loosely mounted upon the split shaft, between a collar 178 confined upon the part 180 of said shaft and a second collar 182 confined upon the part 184, are separating disks 186 preferably made up of laminæ of wood.

It will be seen, from an inspection of Fig. 3 of the drawings, that one part of the split shaft with its attached collar may be taken away from the other leaving the disks 186 and the rolls of fabric upon the other part, and that then the other part may be placed on end with the tapered end down whereupon the disks and rolls will slide off said tapered end and the disks may then be placed again upon the shaft for a new winding operation.

To start the strips to winding the ends are placed between the overlapping parts of the split shaft. When the rolls have been

started the separating disks 186 may be left free as far as control of their position lengthwise of the split shaft is concerned, since the rolls and the collars 178 and 182 take care of that. Until the rolls are started, however, it is advantageous to provide means for spacing the disks 186. The illustrated means comprises forked slides 188 guided in squared openings in lugs 190 of slide holders 192 adjustably confined upon a rod 194 carried by the head 8. The spacing of the slide holders determines the spacing of the disks 186 since the slides are moved rearwardly until their forked ends embrace the edges of the respective disks 186 when new rolls of strips are to be started. As soon as the rolls have been started sufficiently to prevent movement of the disks along the split shaft the slides may be withdrawn from engagement therewith. The forked end of one of the slides near the middle of the row of slides is preferably made long enough so that it will support one part of the split shaft with the disks and rolls thereon when the other part has been withdrawn.

When it is desired to adjust the machine to cut strips of different widths the head 8 may be swung about the stationary shaft 4 thereby uncovering the cutter shafts 130 and 136 and permitting easy access to the disk cutters. When the disk cutters have been adjusted along their shafts to give the desired number of strips of the desired widths, the folders 144 and spacing slides 188 may be adjusted into corresponding positions along their respective supporting rods and the machine will again be ready for operation.

To permit bodily removal of the split shaft from the machine and also to permit relative longitudinal movement of the two parts when placing the ends of the strips between them, the bearings for said shaft are provided with pivoted covers 196 held normally in closed position by locking levers 198 provided with lugs 200 which project over said covers 196.

Having described our invention, what we claim as new and desire to secure by Letters Patent of the United States is:

1. In apparatus of the class described, the combination with means for guiding a plurality of strips to a common winding shaft to be wound into a corresponding plurality of separate rolls thereon, of the said winding shaft, comprising overlapping oppositely tapered parts adapted to receive and clamp between them the ends of said strips, said parts being relatively movable lengthwise to effect the simultaneous clamping or unclamping of the strip ends or the simultaneous release of the wound rolls throughout the extent of the winding part of said shaft, and means at the ends

of said shaft for locking the tapered parts together.

2. In combination, a winding shaft, and a series of separating disks loosely mounted 5 on said shaft, said shaft comprising overlapping parts adapted to be withdrawn from opposite ends of the series of rolls determined by said disks, and said parts having coöperating strip clamping faces so 10 shaped that movement of said parts into and out of disk-supporting relation effects simultaneously the clamping and the unclamping of the strips from which the rolls are formed.

15 3. In a machine of the class described, winding means comprising an obliquely split shaft, a plurality of disks loosely mounted on said shaft, the parts of said shaft being relatively movable lengthwise 20 when said disks are on the shaft to clamp and unclamp the ends of strips guided by said disks, and means for spacing said disks movable into and out of engagement therewith.

25 4. In a machine of the class described, winding means comprising an obliquely split shaft, a plurality of disks loosely mounted on said shaft, the parts of said shaft being relatively movable lengthwise 30 when said disks are on the shaft to clamp and unclamp the ends of strips guided by said disks, and means outside the shaft for spacing said disks.

5. In a machine of the class described, a 35 winding shaft having cylindrical end portions received in bearings in the machine frame and overlapping tapered portions which together form a cylindrical support for separating disks spaced along said shaft, 40 and means for preventing lateral displacement of said overlapping shaft portions constructed to permit relative longitudinal movement thereof into separated relation to each other while still confining said parts 45 against lateral displacement.

6. In a machine of the class described, a winding shaft having cylindrical end portions received in bearings in the machine frame and overlapping portions together forming a cylindrical support for separating 50 disks, said overlapping portions being shaped for relative axial endwise movement into a transversely separated relation to each other, means for preventing lateral displacement of said overlapping shaft 55 portions constructed to permit the aforementioned relative longitudinal movement thereof into separated relation to each other, and connections between one of said parts and a source of power.

60 7. In a machine of the class described, winding means comprising a winding shaft, a plurality of separating disks loosely mounted upon said shaft, spacing means comprising forked slides arranged to embrace the edges of the respective separating disks, and means for supporting said slides constructed to permit their withdrawal out 65 of engagement with said disks when the winding starts.

70 8. In a machine of the class described, winding means comprising a winding shaft formed of overlapping parts arranged for relative longitudinal movement into a transversely separated relation to each other, 75 said parts together forming a support for separating disks, and being movable into and out of strip clamping relation to each other when said disks are in spacing position on said shaft, spacing means comprising forked slides arranged to embrace the edges of the respective separating disks and movable into and out of operative relation to said disks, one of said slides being constructed and arranged to be moved into supporting position beneath said split shaft.
